241,250

INFANT BATH AND LOUNGE SEAT

Sandra H. Fotre, 2351 Siena Court, and Donna I. Boeckman, 2326 N. Indian Hill, both of Claremont, Calif. 91711

Filed July 31, 1975, Ser. No. 600,568

Term of patent 14 years

Int. Cl. D23—02

U.S. Cl. D23—52

FIG. 1 is a perspective view of an infant bath and lounge seat showing our new design in its closed position;

FIG. 2 is another perspective view thereof showing the design in its open position;

FIG. 3 is a side elevational view of FIG. 2, the opposite side being a mirror image of the side shown;

FIG. 4 is a rear elevational view of FIG. 1; and

FIG. 5 is a bottom perspective view of FIG. 1.

We claim:

The ornamental design for an infant bath and lounge seat, as shown and described.
